UNITED STATES PATENT OFFICE.

JOHN KIEWICZ, OF HYDE PARK, MASSACHUSETTS.

SEWING-MACHINE.

1,020,041.

Specification of Letters Patent. Patented Mar. 12, 1912.

Application filed July 24, 1911. Serial No. 640,070.

To all whom it may concern:

Be it known that I, JOHN KIEWICZ, a citizen of the United States, residing at Hyde Park, county of Norfolk, State of Massachusetts, have invented an Improvement in Sewing-Machines, of which the following description, in connection with the accompanying drawing, is a specification, like characters on the drawing representing like parts.

This invention relates to lock stitch sewing machines of that type which employ a stationary shuttle, and the general object of the invention is to provide a sewing machine of this type which has a comparatively simple construction and which can be run noiselessly and at a high speed.

The features wherein my invention resides will be fully hereinafter described and then pointed out in the appended claims.

My invention may be applied to almost any type of sewing machine adapted to make the lock stitch, and as illustrating one application thereof I have shown it as it would be applied to a buttonhole sewing machine of the general type shown in Patents No. 714,284, dated November 25, 1902, and No. 749,776, dated January 19, 1904. I wish it understood, however, that my invention is not limited in its application to buttonhole sewing machines of this type, but can be easily embodied in almost any type of sewing machine.

Referring to the drawings wherein I have illustrated one embodiment of my invention, Figure 1 is a side view of a portion of the bed of a sewing machine as shown in said before-mentioned Patents No. 714,284 and No. 749,776, with a part of the bed broken out to show the construction; Fig. 2 is a top plan view of the shuttle; Fig. 3 is a vertical sectional view through the shuttle and looper-carrying shaft; Figs. 4 and 5 are side views of the shuttle showing different positions of the looper; Fig. 6 is a sectional view through the shuttle on substantially the line $x-x$; Fig. 2; Fig. 7 is a horizontal sectional view through the shuttle on the line $y-y$, Fig. 6; Fig. 8 is a plan view of the shuttle, looper and operating mechanism; Figs. 9, 10 and 11 are plan views of the shuttle and looper showing different positions of the parts in the formation of the stitch; Fig. 12 is a view showing the looper-operating mechanism; Fig. 13 is a plan view of the stationary shuttle support;

Fig. 14 is a plan view of the hold-down; Fig. 15 is a perspective view of the looper; Figs. 16, 17 and 18 are views showing the manner in which the loop is taken from the needle and carried around the shuttle; Fig. 19 is a side view of the shuttle and hold-down; Fig. 20 is a perspective view of the shuttle support.

In the sewing machine herein illustrated A represents a portion of the frame of the sewing machine and A^2 the bed of a sewing machine, such as illustrated in said above-mentioned patents. Situated above the bed is the usual overhanging arm, a portion of which is shown at 1 and which supports the needle 2 that is adapted to reciprocate in a vertical direction. The needle herein shown is an eye-pointed needle through the eye of which the upper or needle thread 3 passes in usual manner. Said needle reciprocates through an aperture in the throat-plate 4 carried by the bed plate A^2 as usual in machines of this description.

The shuttle of the sewing machine is shown at 40 and it is a stationary shuttle situated beneath the throat plate and in position so that the needle reciprocates at one side. This shuttle is an open-topped shell provided with a central hollow stud 6 on which the bobbin 5 is supported in usual manner. On the interior wall of the shuttle is a tension plate 7 provided with an aperture 8 through which the thread passes from the bobbin to an aperture 9 in the shuttle. Said tension plate is a spring plate yieldingly held against the inner wall of the shuttle and bears against the shuttle thread, as will be obvious.

The shuttle 40 is sustained on a stationary support or platform 9 which is centered and held in the proper position by the shaft 10 that carries the looper 11. This shaft 10 is mounted for turning movement in a bearing 12 carried by a bracket 13 fastened to the underside of the bed plate A^2 and it has at its lower end a pinion 14 that meshes with and is driven by a segmental rack 15 carried on a swinging arm 16. Said arm is pivotally mounted intermediate of its ends, as at 17, to any suitable support and is operated by a cam 18 fast on the driving shaft A^5 . This cam 18 is constructed to vibrate the arm 16 thereby to oscillate the shaft 10. Fast to the upper end of the shaft 10 is a looper-carrying arm 19 which carries the looper 11, said looper being arranged to turn

about the exterior of the shuttle close to the periphery thereof. The looper is of special shape, it having a nose 20 to enter a loop of needle thread, and a lug 21 to engage 5 said loop and retain it on the looper. The operation of the looper will be more fully hereinafter described.

The upper end of the shaft 10 is provided with an axial recess 22 which receives a 10 stud 23 secured to and depending from the shuttle support 9, said stud being stationary with the shuttle support but operating to hold the shuttle support in its proper position. The shuttle 40 rests loosely on the stationary shuttle support 9 and is secured in place partly by a hold-down 24 and partly by a positioning finger 25. The hold-down is shown in Fig. 14 and is in the form of a plate which is fastened at one end to the 15 bed of the machine, as at 26, and is provided with a point 27 that overlies one edge of the shuttle and with a finger 28 that not only overlies the upper edge of the shuttle but enters the shuttle slightly, as clearly seen 20 in Fig. 3. The upper edge of the shuttle is provided with a shoulder 29 adjacent the point 27, which shoulder coöperates with the point 27 to prevent turning movement of the shuttle clockwise in Figs. 9 and 10. 25 The positioning finger 25 is fastened to the bed of the machine in any suitable way, as by a screw 30, and it is adapted to coöperate with another shoulder 31 formed on the top edge of the shuttle as shown in Figs. 4 and 30 5, thereby to prevent the shuttle from turning in the opposite direction. These two shoulders 29 and 31, together with the point 27 and finger 25 prevent the shuttle from turning in either direction and the hold-down 24 prevents the shuttle from rising 35 and from lateral movement while permitting it to be readily removed from the support by tipping up the edge of the shuttle opposite the hold-down. The shuttle support 40 9 is also provided with the lip or flange 32 which assists in positioning the shuttle.

The shuttle support 9 is held from rotary movement by means associated with the hold-down. As herein shown said shuttle support 50 is provided with the vertical flange 33 having an apertured ear 34 extended therefrom and a pin 35 depending from the hold-down enters the aperture in the ear and thus holds the shuttle support from rotation.

55 In the operation of the device the needle is depressed through the throat - plate, as seen in Fig. 1, and at this time the looper is situated back of the needle, as shown in Fig. 9. As the needle begins its retracting movement a slight loop or slackness is formed in the needle thread 3 and the looper is at this time swung forwardly into the position shown in Fig. 10 so that the nose thereof will pass in behind the needle and enter the 60 65 loop 49 of the needle thread. It is under-

stood, of course, that when the needle is in its lowest position the point of the needle stands above the arm 19 so that the looper can swing around the needle without coming in contact therewith. As the needle is 70 retracted the looper continues its forward swinging movement into the dotted line position Fig. 10, during which movement it draws on and enlarges the loop 49 of needle thread and carries said loop around the 75 shuttle, as seen in Fig. 4. The shuttle is provided on its side with a loop-opening projection or portion 41 which is shown as a wedge-shaped portion having the two converging shoulders or walls 42. As the 80 looper is moved about the shuttle from the full to the dotted line position shown in Fig. 10 or from the position shown in Fig. 4 to the position shown in Fig. 5, the point 43 of the loop-opening portion enters the loop 85 49 and the two sides of the loop move down over the inclined shoulders 42 and thus said loop-opening projection 41 insures that the loop will be opened properly to receive the shuttle. In fact the upper and lower 90 branches of the loop naturally slide over the top and bottom of the shuttle so that when the loop has been carried around into the position shown in Fig. 11 it is carried entirely over the shuttle. When the looper 95 reaches the position shown in Fig. 11 the usual take-up (not shown) operates to take up the needle thread, during which operation the loop is shed from the looper and the latter begins its backward movement 100 into initial position again. The take-up operates to set the stitch in usual manner, the tension plate 7 supplying the requisite tension to the shuttle thread. As the needle makes its next descent the take-up gives up thread as usual in sewing machines of this type for the formation of the next stitch. During the operation of the device the loop passes between the shuttle and the stationary shuttle support 9 and also between the shuttle and the hold-down, it being understood that sufficient space is provided between these parts to readily permit the loop to pass over the shuttle.

It will be seen from the above that my 115 invention is comparatively simple and comprises few parts and because of this fact the sewing machine can be run at a comparatively high speed.

Having fully described my invention, 120 what I claim as new and desire to secure by Letters Patent is:—

1. In a sewing machine, the combination with a looper-carrying shaft, of a horizontal shuttle support sustained by the shaft, 125 means for holding said support stationary, a stationary shuttle resting on the support and provided with a shoulder on its upper edge, a horizontal finger to engage said shoulder and prevent the shuttle from turn- 130

ing, a needle, and a looper carried by the shaft and moved thereby in a path exterior to the shuttle and in a plane at right angles to the needle path.

5 2. In a sewing machine, the combination with a needle, of a stationary shuttle support, a stationary shuttle sustained on said support and provided on its upper edge with a shoulder, a looper, means to move 10 the looper about the shuttle in a circular path thereby to carry a loop of needle thread around the shuttle, a hold-down for the shuttle to prevent it from rising and also to hold it from turning in one direction, and a finger engaging the shoulder of the shuttle and preventing it from turning in the other direction.

3. In a sewing machine, the combination with a stationary shuttle having two oppositely-disposed shoulders on its upper edge, of means for supporting the shuttle, a needle, a looper, means to move the looper in a circular path exteriorly to the shuttle thereby to carry a loop of needle thread 25 thereabout, a hold-down to engage the upper edge of the shuttle and coöoperating with one of said shoulders to prevent turning movement of the shuttle in one direction, and a finger coöoperating with the other 30 shoulder to prevent turning movement of the shuttle in the other direction.

4. In a sewing machine, the combination with a vertically-arranged shaft having an axial recess, a looper sustained by said shaft, 35 a stationary platform provided with a stud entering said recess and positioned thereby, a shuttle on the platform and provided with a shoulder, a stationary hold-down to engage the top of the shuttle and prevent it 40 from rising and to engage said shoulder to prevent the shuttle from turning, and a needle, said looper operating to take a loop of needle thread and carry it around the shuttle.

45 5. In a sewing machine, the combination with a needle, of a horizontal stationary platform adjacent the path of the needle, a stationary shuttle supported by the platform and provided with a shoulder, a hold-down engaging the top of the shuttle to hold the latter from rising and coöoperating 50 with said shoulder to hold said shuttle from turning, and a looper to take a loop of needle thread and carry it around the shuttle.

55 6. In a sewing machine, the combination with a needle, of a stationary platform adjacent the path of the needle, a stationary

shuttle supported by the platform, a stationary hold-down engaging the top of the 60 shuttle to hold the latter in position, a looper to take a loop of needle thread and carry it around the shuttle, said platform having a flange rising therefrom, and means connecting said flange to the hold-down 65 thereby to prevent the platform from turning.

7. In a sewing machine, the combination with a needle, of a shaft having an axial recess, a platform having a stud entering 70 said recess and positioned thereby, a stationary shuttle on said platform, a hold-down for the shuttle provided with means to prevent said shuttle from turning, and a looper carried by said shaft and adapted to 75 take a loop of needle thread and pass it around the shuttle.

8. In a sewing machine, the combination with a needle, of a shaft having an axial recess, a platform having a stud entering 80 said recess and positioned thereby, a stationary shuttle on said platform, a hold-down for the shuttle, said platform having a flange rising therefrom, means connecting said flange to the hold-down thereby to prevent the platform from turning, and a looper carried by said shaft and adapted to 85 take a loop of needle thread and pass it around the shuttle.

9. In a sewing machine, the combination 90 with a stationary shuttle, of a needle, a looper to take a loop of needle thread and carry it around the shuttle, said shuttle having a shoulder on its upper edge, and a hold-down provided with a point overlying 95 said upper edge of the shuttle adjacent the shoulder and also provided with a down-turned finger to overlie and enter the shuttle.

10. In a sewing machine, the combination 100 with a stationary shuttle, of a needle, a looper to take a loop of needle thread and carry it around the shuttle, and a hold-down to engage the top of the shuttle and prevent the latter from rising, said hold-down being provided with a down-turned 105 finger to enter the shuttle and prevent lateral movement thereof.

In testimony whereof, I have signed my name to this specification, in the presence 110 of two subscribing witnesses.

JOHN KIEWICZ.
